UNITED STATES PATENT OFFICE.

CHARLES W. BURTON, OF SALT LAKE CITY, UTAH.

TRACK-LAYING MACHINE.

1,177,301.

Specification of Letters Patent. Patented Mar. 28, 1916.

Application filed December 8, 1915. Serial No. 65,748.

To all whom it may concern:

Be it known that I, CHARLES W. BURTON, a citizen of the United States, residing at Salt Lake City, in the county of Salt Lake 5 and State of Utah, have invented a new and useful Improvement in Track-Laying Machines, of which the following is a specification.

This invention relates to an improvement 10 in track laying machines, and the object is to provide means for conveying the rails and ties from the flat cars to a point beyond the cars and depositing the rails and ties in building the road.

15 The invention consists of certain novel features of construction and combinations of parts which will be hereinafter described and pointed out in the claims.

In the accompanying drawings:—Figure 1 20 is a view in side elevation of the invention; Fig. 2 is a rear end view; Fig. 3 is a view in side elevation of the tie carrier and tie truck; Fig. 4 is an end view of the tie carrier; Fig. 5 is a view in side elevation of the 25 rail carrier; Fig. 6 is a top plan view of the rail carrier; Fig. 7 is an end view; Fig. 8 is a perspective view, showing diagrammatically the manner of operating the rail carrier, and rail hoist. Fig. 9 is a detail view 30 in elevation showing the manner of manipulating the clutches for connecting the winding drums to the driven shaft; Fig. 10 is a detail view in end elevation of one of the clutches and levers; and Fig. 11 is a detail 35 perspective view showing the forward portions of the three I-beams or tracks.

A, represents the track laying frame, mounted on trucks 2.

Connected to upper part of the frame A, 40 and extending longitudinally thereof, are three I-beams or tracks 3, 4 and 5. The tracks 3 and 5 support the rail carriers B, which are provided with wheels 6 which support the rail carriers and travel along 45 the tracks. The track 4 supports the tie-carrier C which is provided with wheels 7 which are mounted on the track 4.

A platform 8 is mounted on the top of the framework A, upon which is an engine or 50 motor 9, and supported upon the frame is a transverse driving shaft 10 which is rotated by the engine or motor 9 by a belt 11.

Mounted on the shaft 10 are a plurality 55 of winding drums, each carrier being provided with two drums, a drum for causing the carrier to be drawn forward and a drum for returning the carrier. A drum is pro-

vided for each rail-carrier for hoisting the rails to the carrier. The rail-carrier forward drums 12 have a cable or rope 17 connected thereto which passes around a pulley 18 on frame A, and thence around a pulley 19 located near the end of the track 3, and the end of the cable is connected to the forward end of the rail carrier B. The return winding drum 13 of each rail carrier has a rope or cable 20 connected thereto, which passes around a pulley 18 and then around a pulley 21 on the rear end of the track 3, and the terminal of the cable is connected to the rear end of the rail carrier B. The winding drums are all loosely mounted on the driving shaft 10, and each is provided with a clutch 22 which is engaged by a movable clutch member 23 on the shaft 10. 75 Each clutch member 23 is provided with a lever 24 for operating it, so that when a clutch member is thrown into engagement with a winding drum 12, the return winding drum 13 remains loose and free to rotate for 80 the purpose of paying out the cable to permit the rail carrier to travel along the track 3. This same operation is true of both rail carriers and tie carrier. When it is desired to return the tie or rail carrier to its 85 original position the forward winding drum clutch member is disengaged and the return winding drum clutch member, is thrown into engagement with the return winding drum, so that the cable will be wound on the 90 return winding drum, and the cable paid out from the forward winding drum.

In Figs. 1 and 2, one of the rail carriers is omitted so that it may be understood how the tie-carrier C is operated. Referring to 95 Fig. 1, the rope or cable 25 on the forward winding drum 14 passes around one of the pulleys 18, and then around a pulley 26 located at the forward end of the track 4, the terminal of the rope or cable being secured 100 to the forward end of the tie-carrier C. The return winding drum 15 has its cable 27 passing around a pulley 18, and then around a pulley 28 located near the rear terminal of the track 4, and the cable is then connected to the rear end of the tie-carrier C. By manipulating the levers 24 the tie carrier may be moved forward or rearward in the same manner as described in the operation 105 of the rail-carrier.

Mounted on a shaft 29 journaled in the body of the rail-carrier B is a winding drum 30. Another shaft 31 is journaled on the body of the rail carrier, and each shaft 29

and 31 is provided with a gear wheel 32 which meshes with an idler gear 33 mounted on the rail carrier B, so that both shafts will rotate in the same direction. Grooved 5 wheels 34 are mounted on the shafts 29 and 31. A cable 35 is connected to the body of rail carrier about midway of its length, and the terminals of the cable pass around the grooved wheels 34 and are connected to a 10 counter-weight 36, which when raised to the position shown in Figs. 1 and 8 by the cable 37 which is connected to the counter-weight, and passes over a pulley 38 on the rail carrier B, releases the shafts 29 and 31 and 15 permits them and the drum 30 to rotate. The counterweight when released by the operator, tightens the cable 37 causing the shafts 29 and 31, and drum 30 to be held stationary.

20 Cables 39 are connected to each of the shafts 29 and 31, and connected to the free ends of the cables 39 are rail grapples 40. Rail hoisting drums 16 mounted on the shaft 10 have cables 41 connected thereto 25 which pass around pulleys 18, then around pulleys 42 connected to the rails 3, and then around winding drum 30 of the rail-carrier. The cable is then passed around a grooved wheel 42 on the frame A, and then to a winding 30 drum 43, which is operated by an attendant on the flat car (not shown).

The tie-carrier C has its sides hinged as at 44, and the lower ends are provided with 35 openings 45, for the reception of the ends of rollers or bars 46, which are placed in transverse grooves 47 formed in the tie truck D. The sides of the tie carrier are adapted to be swung over the ends of the rollers 46 when the tie carrier is placed in position 40 over the tie truck, and as the tie carrier is drawn forward, the tie truck is caused to travel down the inclined way 48 until it strikes a bumper 49. When the tie truck travels down the inclined way 48 the load of 45 ties will be supported entirely by the tie-carrier and the rollers 46 disengaged from the tie-truck.

A swinging platform 50 is located along one 50 side of the frame A, for the purpose of receiving the empty tie-trucks D, so that they may be conveyed back to the flat cars to be again loaded with ties, and taken from the path of the oncoming tie-trucks and rails. The platform is intended to be swung up 55 alongside of the frame A when not in use.

From the foregoing it will be seen that the several drums 12, 13, 14, 15 and 16 may be operated simultaneously or independently, and the same is true of the tie-carrier and 60 rail carriers.

I claim:—

1. In a track laying machine, the combina-

tion with a frame having a plurality of aerial tracks, of a tie carrier and rail carriers mounted to travel on said tracks, a 65 driving shaft having a plurality of winding drums mounted thereon, one drum for each carrier for causing the carrier to move in one direction, and a drum for each carrier to cause it to travel in the opposite direction, means for connecting the carriers to the drums, and means for rotating the shaft.

2. In a track laying machine, the combination with a frame having a plurality of aerial tracks, of a tie carrier and rail carriers mounted to travel on said tracks, a driving shaft having a plurality of loosely mounted winding drums thereon, one drum for each carrier for causing the carrier to travel in one direction, and a drum for each carrier to cause it to travel in another direction, means for connecting the carriers to their respective drums, means for rotating the shaft, and means for locking the drums to the shafts, one drum for each carrier being locked to the shaft at a time.

3. In a track laying machine, the combination with a frame having a plurality of aerial tracks, of a tie carrier and rail carriers mounted to travel on said tracks, means for causing the carriers to be conveyed in either direction on said tracks, an inclined way mounted on the frame, a tie truck adapted to travel on said way having rollers thereon on which the ties are mounted, said tie carrier being provided with hinged sides, said sides being provided with means for engaging the rollers, whereby when the carrier is caused to travel along the track, the tie truck is carried thereby until the tie truck 100 in its descent causes the disengagement of the rollers therewith so that the load of ties is supported by the tie carrier.

4. In a track laying machine, the combination with a frame having an aerial track, 105 of a rail carrier mounted to travel on the track, means for conveying the carrier in either direction on the track, rotatable shafts mounted on the carrier and inter-geared so that they will rotate in unison, grapples connected to the shafts by flexible means, and adapted to engage and support the rails, a winding drum mounted on one of the shafts, means for operating the drum for causing the grapples and rails to be elevated, means 115 connected to the shafts for holding them against rotation, and means for operating said holding means whereby the shafts may be rotated.

CHARLES W. BURTON.
